UNITED STATES PATENT OFFICE.

WILLIAM W. McLAREN, OF BIRMINGHAM, ALABAMA.

PROCESS OF RECORDING PHONOGRAPH RECORDS.

Application filed April 18, 1927. Serial No. 184,656.

This invention aims to provide a novel process and means for making phonograph records.

It is within the province of the disclosure 5 to improve generally and to enhance the utility of devices of that type to which the invention appertains.

With the above and other objects in view which will appear as the description proceeds, the invention resides in the combination 10 and arrangement of parts and in the details of construction hereinafter described and claimed, it being understood that changes in the precise embodiment of the 15 invention herein disclosed, may be made within the scope of what is claimed, without departing from the spirit of the invention.

In the accompanying drawing, the invention is shown in a single vertical sectional 20 figure, wherein parts appear in elevation.

In carrying out the invention, there is provided a receptacle 1 of any desired shape and size, supported on a base 2, a compressible gasket 3 being interposed between the 25 base 2 and the receptacle 1, clamps 4 holding the parts 1, 2 and 3 in air-tight relation. A pipe 5 is mounted at one end in the base 2 and is in communication with the receptacle 1, the outer end of the pipe 5 being connected 30 to a pump 6 or other instrumentality whereby air may be withdrawn from the receptacle 1, the process being carried out in a vacuum, meaning thereby as close an approximation of a perfect vacuum as can be obtained by known means. A shut-off valve 7 is interposed in the pipe 5, and a relief valve 35 8 is interposed in the said pipe, the valve 8 being disposed between the valve 7 and the receptacle 1. Conductors 9 are mounted air-tight in the side of the receptacle 1 and are joined to terminals 10 which are accessible from inside the receptacle 1. Conductors 11 40 are mounted in the receptacle 1, in spaced relation to the conductors 9, and are joined to terminals 12 which are accessible from inside the receptacle 1, the conductors 11 being adapted to cooperate with any well known electrical means for amplifying sound (not shown).

On the base 2 is mounted the casing 14 of 50 a motor which, preferably, is electrically driven. The casing 14 is provided with spring contact tongues 15, adapted to cooperate with the terminals 10 when the receptacle 1 is mounted on the base 2, as shown

in the drawing. Owing to the way in which the parts 15 and 10 cooperate, electric current is supplied to operate the motor. There is a standard 16 on the casing 14, the standard carrying spring switch tongues 17 which are insulated from each other, the switch tongues 17 being adapted to cooperate with the terminals 12 in the way hereinbefore described in connection with the terminals 10 and the switch tongues 15. Conductors 18 60 lead from the switch tongues 17 to an electrically operated recording mechanism 19 which is supported at 20 on the casing 14 in such a way that the stylus 23 of the recording mechanism 19 may cooperate with a master record 21 carried by a turntable 22 which is operated by a motor in the casing 14. 70

In practical operation, when the parts are arranged as shown in the drawing, the air is withdrawn from the receptacle 1, by way of the pump 6 or its equivalent, and the shut-off valve 7 and the relief valve 8 are closed to maintain the vacuum or partial vacuum which has been obtained in the receptacle 1. The motor is operated by current derived 80 from the conductors 9, or in any other suitable way, to rotate the turntable 22 and the record 21 with respect to the stylus 23 of the recording mechanism 19. The result is that the master record is produced in vacuo. A 85 maximum effect of the stylus movement is obtained, there being no air-pocket in front of the stylus. Moreover, since there is no circulation of air or draft, dirt, grit, and other foreign substances, cannot accumulate 90 on the record or on the point of the stylus, during recording, to impede the full and proper performance of the stylus.

Not only may the master record be made in a vacuum, but, if desired, the commercial 95 records from the master record may be made in a vacuum, also.

What is claimed is:—

1. A method of making a master phonograph record, which consists in inscribing it 100 in a vacuum.
2. In a device of the class described, an air-tight receptacle, means for withdrawing air from the receptacle, a recording mechanism in the receptacle, and means for operating the recording mechanism from a point 105 external to the receptacle.

In testimony that I claim the foregoing as my own, I have hereto affixed my signature.

WILLIAM W. McLAREN.
